UNITED STATES PATENT OFFICE.

SVEN WILLIAM OSTHAGEN, OF WOODRIDGE, NEW JERSEY, ASSIGNOR TO MILTON
PIANO COMPANY, A CORPORATION OF NEW YORK.

DESIGN FOR A PIANO-CASE.

49,074.

Specification for Design.

Patented May 16, 1916.

Application filed March 9, 1916. Serial No. 83,202. Term of patent 7 years.

To all whom it may concern:

Be it known that I, SVEN WILLIAM OSTHAGEN, a citizen of the United States, residing at Woodridge, in the county of Bergen and State of New Jersey, have invented a new, original, and ornamental Design for Piano-Cases, of which the following is a specification, reference being had to the accompanying drawing, forming part thereof.

The figure is a perspective view of a piano case, showing my new design.

I claim:

The ornamental design for a piano case, as shown.

SVEN WILLIAM OSTHAGEN.
